MOLDED FLOORING MATERIAL

Harry M. Austin, Baltimore, Md., assignor to
 Crown Cork & Seal Company, Inc., Baltimore,
 Md., a corporation of New York

Application January 8, 1937, Serial No. 119,702

3 Claims. (Cl. 20—79)

The present invention relates to molded flooring material.

The principal object of the invention is to provide a molded flooring material which may be secured to any floor surface, and which has optimum anti-slipping and wearing qualities, combined with a high degree of resiliency.

Another object of the invention is to provide a resilient and non-slip stair tread which is particularly constructed to meet the peculiar problems encountered in such types of floor covering.

Other objects and advantages of the invention will appear from the following specification and drawing, wherein:

15 Figure 1 is a plan view of a body of material of the present invention.

Figure 2 is a sectional view taken on the line 2—2 of Figure 1.

20 Figure 3 is a view similar to Figure 2 showing a sheet provided with a different type of securing means.

Figure 4 is a view similar to Figure 2 of a modified form of the invention.

Figure 5 is a plan view of a stair tread constructed in accordance with my invention, and

25 Figure 6 is a sectional view taken on the line 6—6 of Figure 5.

30 Referring to Figures 1 and 2, wherein a body of the material of the invention is shown, the numeral 10 designates an upper and wear receiving sheet or layer and the numeral 11 indicates a base sheet. The body of the sheet 10 is of rubber or phenolitic resin and has particles 12 of a material having resilient and non-slip characteristics such as cork, and particles 13 of abrasive such as sharp sand, emery or Carborundum incorporated therein. The base sheet 11 may be formed of metal, rigid fibre or phenolitic resin and is joined to the sheet 10 by vulcanization.

35 The proportions of cork and rubber in the layer 10 may be varied to meet different requirements, the anti-slipping characteristics of the layer being increased if a large proportion of cork is used and in large particles, even though a small proportion of abrasive is used, while the resiliency of the material may be varied by varying the proportion of rubber. It will be understood that since cork is resilient, the material will retain its resilient qualities even if the quantity of 40 rubber is sharply reduced, and the rubber may therefore be relied upon chiefly for its characteristics as a binder. The particles 13 of abrasive will increase the anti-slipping qualities of the material but the efficiency of the material for 45 anti-slipping purposes is not due to the presence

of these particles alone, because cork has a high coefficient of friction. Also, in use, particles of grit will become embedded in the cork, thereby increasing the anti-slipping characteristics of the material. Furthermore, since the rubber will ordinarily wear more rapidly than the cork, the cork particles will protrude slightly above the surface of the rubber, and the material will lose none of its anti-slipping characteristics by reason of wear.

5 10 If hardness rather than resiliency is desired for some particular installation, the same bulk of cork may be used, but in small particles, and more abrasive should be used. The use of a resin instead of rubber will also naturally increase the hardness of the material. In any event, if cork is used, the material will have a high degree of resiliency, because of the fact that cork is bodily compressible. In other words, regardless of the relative hardness of the binder of rubber or resin, 15 the presence of relatively large particles of cork will give the entire material a high degree of resiliency.

20 25 Figure 5 is a plan view of a stair tread constructed in accordance with my invention, and Figure 6 is a sectional view taken on the line 6—6 of Figure 5.

25 30 If a phenolitic resin instead of rubber is used for the body of the sheet 10, the resin should be of such type that reversion will occur at a lower temperature than that which will char or destroy cork. Cork becomes charred at 450° F., and the reversion of the resin should therefore occur at a temperature not greater than 300° F. If rubber is used, the sheet 10 will be vulcanized at a temperature not greater than 300° F. In any event, the layers 10 and 11 will be secured to each other during vulcanization.

35 40 With the resilient layer 10 vulcanized to a rigid lower sheet 11, no curling of the layer 10 can occur. Also, the rigid sheet 11 can be attached to a sub-flooring or other supporting surface much more securely than is the case with a resilient preformed layer alone, or a resilient layer which must be troweled upon a sub-flooring.

45 In the form of the invention illustrated in Figures 1 and 2, the upper sheet 10 has apertures 16 provided therein and the base sheet 10 provided with concentric but smaller apertures 17. In order to secure the material to a flooring or sub-flooring indicated by the numeral 18, bolts 19 are positioned in the apertures 16 and 17 to extend through apertures in the flooring 18. After the material comprising the layers 10 and 11 has 50 been secured to the flooring 18, a body of self-vulcanizing material 20 may be inserted in the apertures 16, this material preferably having the same degree of resiliency and the same wearing qualities as the material itself.

In the form of invention disclosed in Figure 3, the bolts 19 are positioned in the material of the invention during molding of the same.

In the form of material shown in Figure 4, a base sheet 21 formed of canvas or similar heavy fabric is cemented to the layer 10, the use of a fabric for the base layer rendering the material flexible. The fabric may be cemented or riveted to the upper layer and securing means such as 10 shown in Figures 1 to 4 may be used, or the material may be cemented to a flooring.

Figure 6 shows a form of stair tread produced in accordance with the present invention and which comprises a rigid base plate 22 having one 15 end portion 23 curved to fit beneath the outer edge of a stair tread indicated at 24. The upper layer 25 is suitably secured to the base layer 22 and extends about the end portion 23 of the base layer as shown in Figure 6. The base layer 22 20 may be secured to the tread 24 by either of the arrangements disclosed in Figures 1 to 4. The portion of the layer 25 adjacent the edge of the tread, and indicated by the numeral 26, contains a relatively large quantity of finely divided cork 25 particles and a relatively large quantity of abrasive, thus rendering this portion of the tread harder and maintaining proper anti-slip protection. The remainder of the layer 25, indicated by the numeral 27, includes larger cork particles 30 so that it will have a high degree of resiliency. By the above distribution of large and small cork particles, the wearing problems peculiar to stair treads are very efficiently met. It is found in practice that persons ascending steps will place 35 the ball or more resilient portion of a foot upon the outer portion of the tread. Considerable wear therefore occurs at this point, and a high degree of resiliency is not required. These conditions are entirely met by the use of a large 40 quantity of small particles of cork in the portion 26 of the tread. On the other hand, persons descending steps place their heels upon the body portion of the tread, indicated in Figure 6 by the numeral 27, and a high degree of resiliency is 45 required at this point to give a more comfortable tread.

The tread disclosed in Figures 5 and 6 therefore meets all of the problems involved in stair treads, and with full anti-slip qualities.

It will be observed that all of the forms of the invention are molded, and they may thus be 5 formed under proper control. It is found that materials adapted to be mixed by troweling upon a flooring or sub-flooring are not of uniform mixture and, furthermore, troweled materials cannot be attached as securely to a flooring as 10 can the materials of the present invention.

It will be understood that the invention is not limited to the details of construction shown in the drawing, and that the examples of the uses of the material which have been given do not 15 include all of the uses of which it is capable; and that the phraseology employed in the specification is for the purpose of description and not of limitation.

I claim:

1. A molded stair-tread covering comprising a portion adapted to be positioned adjacent the outer edge of the tread and of such composition as to be relatively non-resilient, but with high non-slip characteristics, and a portion adapted to 25 be positioned over the body of the tread, and of such composition as to have higher resilient characteristics than the first-named portion.

2. A molded stair-tread covering comprising a portion adapted to be positioned adjacent the 30 outer edge of the tread and including relatively small particles of a material having non-slip and resilient characteristics, and a portion adapted to be positioned over the body of the tread including larger particles of said material.

3. A molded stair-tread covering comprising a portion adapted to be positioned adjacent the outer edge of the tread and including relatively small particles of cork, and a portion adapted to be positioned over the body of the tread and including larger particles of cork, the particles of cork being so exposed in the tread and wear receiving surfaces of said portions as to retain their anti-slip and resilient characteristics.
